UNITED STATES PATENT OFFICE

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF MASSACHUSETTS

COPYING LATHE

Application filed February 9, 1928. Serial No. 253,068.

This invention relates to copying lathes and is illustrated as embodied in a last lathe.

In the ordinary last lathe both the right and left lasts are turned from a single right model, the model and block being rotated in the same and in opposite directions, called "direct" and "reverse" cutting, respectively, in the two cases.

In order to secure perfect reproduction of rights and lefts it is necessary that, in reverse cutting, where a left is reproduced from a right model, the model and the last block be always reversely and symmetrically situated relatively to the model wheel and cutter. In other words, they must have been rotated at all times equally relatively to the plane containing their axis of rotation and the model wheel and cutter centers. Such a plane has been called the "(width) grading plane", and will be herein so designated, though there is no question of width grading involved in the present invention. When a swing frame is used its angular movement is compounded with those of the oppositely rotating model and block, and since the reverse driving mechanism is mounted in the swing frame itself, so that the model and block rotate equally and oppositely relatively to the swing frame, they are not rotated equally and oppositely relatively to the grading plane in all positions of the swing frame, which causes a relative twist in them about their longitudinal axes, which is strongly observable by comparison of localities of varying heights. The problem of direct reproduction involves no difficulty because the model and block maintain the same behavior relatively to the grading plane, and whatever that behavior may be, accurate reproduction will result. An object of the present invention is to avoid the above-described difficulty in the case of reverse reproduction. This is accomplished by providing a swinging member carrying the reversing mechanism and having a plane fixed in it which is always coincident with the grading plane. As disclosed, this member is a secondary swing frame affording a second connection between the primary swing frame and the machine, so constructed that its connections with the primary swing frame and with the main

frame are at the same distance from the pivotal axis of the primary swing frame as is the model wheel axis. This secondary frame carries the transmission gearing between the model and the block and, therefore, I am enabled to effect equal rotation of the model and block in opposite directions relatively to the grading plane. 55

The above-mentioned and other features of the invention will be better understood from 60 the following description of one embodiment of the invention taken in connection with the drawing representing those parts of the machine necessary for the understanding of the invention. 65

In the drawings,

Fig. 1 is a view in perspective of parts of a last lathe embodying the invention, and

Fig. 2 is a diagrammatic projection, from the side, of the parts shown in Fig. 1. 70

The machine shown is a last lathe of ordinary construction such as for example, is shown in United States Letters Patent No. 544,891, granted August 20, 1895 to W. F. Gilman. Only so much of the machine is 75 shown as is material to the present invention.

The frame of the machine is indicated at 10. The pivots of a primary swing frame 14 are indicated at 12-12. The spindles of the model and work, a last block, which rotate in the frame 14 are represented at 16 and are driven by any desired train of gearing 18-20-22 from the center 12, the pivotal axis in the frame. The gear 22 is integral with the model driving dog and can be regarded as the model itself. 80

A secondary swing frame 24 is pivoted on the spindle axis 16 and is connected to the main frame of the machine at 26 by a sliding connection shown as a pin-and-slot connection 28, the axis of the slot passing through the axis 16. This construction permits the swinging of both swing frames 14 and 24. The cutter and model wheel centers are represented by the points 30, 32 respectively, and the grading plane is 16-30-32. 85

In the embodiment of the invention disclosed, the centers 16, 28 and 30 are all equidistant from the center 12, and consequently 100

a circle 34 can be passed through them, around this center (Fig. 2).

A transmission gearing is mounted in the secondary frame 24 and comprises a transmission shaft 36 running from the model to the block and driven by a gear 38 mounted on it, which meshes with the gear 22. For driving the block, the transmission gear comprises an idler 40 which can be inserted at will between a gear 42 like the gear 38 mounted on the shaft 36, and a gear 44 like the gear 22 mounted on the block spindle 16, in order to effect reverse drive. In Fig. 1 the gears are thus shown. For direct drive the gear 40 is removed and the gears 42-44 are engaged.

It is clear that as the model rotates the swing frames 14 and 24 swing in and out corresponding to irregularities in the model surface, and the grading plane 16-30-32 moves as the axis 16 swings about the center 12. It will now be shown that the secondary swing frame 24 contains a plane which will always be coincident with the grading plane, or, in other words, that the orientation of the secondary swing frame 24 relatively to the grading plane remains unaltered. This being assumed for the present, it will be clear that if the reversing gearing in the secondary swing frame be arranged to rotate the model and block equally relatively to this fixed plane the model and block will always be symmetrically located relatively to the grading plane, as is desired.

Returning now to Fig. 2, consider the effect of rotating the primary swing frame 14 about the center 12. This will cause the axis 16 to move around the circle 30-16-26, and the slot 28 will slide correspondingly on the pivot 26. The angle 26-16-30 formed by the lines 16-26 and 16-30, being always measured by one-half the arc 26-30 on the circle 34, remains unchanged in value, and the line 16-30 can therefore be regarded as fixed to the secondary frame 24. This line 16-30 can thus be regarded as defining a plane fixed in the secondary swing frame 24 (and moving with it) which always passes through the axis 16 and the axes 30, 32, and therefore coincides with the grading plane, irrespective of swing frame rotation.

Now suppose for the moment that the mechanical drive is stopped, and the swing frame rotated through a certain angle. This will in general cause a rotation of the gear 22 (which also represents the model) relatively to the system 24-16-30 which has just been provided to be integral. The two gears 38 and 42 and the reversing idler 40 being mounted in this system will cause an exactly equal and opposite rotation of the block-gear 44 with regard to the system 24-16-30 about the center 16, which is in the grading plane. The model and block have thus been rotated equally in opposite di-

rections from the grading plane 16-30-32, and accurate right and left reproduction results. Clearly the continuous operation of the mechanical drive does not affect this condition in any way.

In the above-described embodiment of the invention, reverse cutting is effected by reversing the rotation of the block. It can also be obtained by reversing the rotation of the model, and nothing in the theory is altered by this change in procedure. It is only necessary that the reversing gearing be mounted on a member having an invariable plane always coincident with the grading plane.

In order to simplify the wording of the above specification and of the appended claims I have described the relations of the parts as seen in Fig. 2 which is an orthogonal projection of the parts as seen from the end of the machine.

Having described my invention, what I claim as new and desire to secure by Letters Patent of the United States is:

1. In a copying lathe, a model wheel and a cutter, a swing frame arranged to carry a model and a block and pivoted on the main frame of the machine, and a second swinging member carrying reversing gearing between the model and the block, said second swinging member being pivoted on the swing frame and having a pivoted sliding connection with the main frame of the machine, the pivot of said sliding connection, the pivotal connection between the swing frame and the second swinging member, and the center of the model wheel all being equidistant from the pivotal connection of the swing frame with the main frame.

2. In a copying lathe, a model wheel and a cutter, a swing frame arranged to carry a model and a block and pivoted on the main frame of the machine, and a second swinging member, pivoted on the swing frame and having a sliding pivotal connection with the main frame of the machine, the axis of the slide passing through the pivotal connection between the swing frame and the second swinging member, a gear mounted in the swing frame on the model axis and driven from the pivotal axis of the swing frame, a gear train driven by the first-mentioned gear and comprising a reversing gear mounted in the second swinging member, and a gear mounted in the swing frame on the block axis and driven from the gear train, the pivotal axis of the swing frame being equidistant from the model wheel axis the pivotal connection between the swing frame and the second swinging member, and the said sliding pivotal connection.

3. In a copying lathe, a model wheel and a cutter, a swing frame arranged to carry a model and a block and pivoted on the main frame of the machine, and a second swinging member pivoted on the swing frame and hav-

ing a sliding pivotal connection with the main frame of the machine located on the frame at a substantial distance from the grading plane, the axis of the slide passing through the pivotal connection between the swing frame and the second swing member, a gear mounted in the swing frame on the model axis and driven from the pivotal axis of the swing frame, a gear train driven by the first-mentioned gear and comprising a reversing gear mounted in the second swinging member, and a gear mounted in the swing frame on the block axis and driven from the gear train, the pivotal axis of the swing frame being equidistant from the model wheel axis, the pivotal connection between the swing frame and the second swinging member, and the said sliding pivotal connection.

20 In testimony whereof I have signed my name to this specification.

LAURENCE E. TOPHAM.
